(57) **CLAIM**

The ornamental design for a lavatory basin, as shown and described.

DESCRIPTION

FIG. 1 is a top perspective view of a lavatory basin design showing my new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an exploded perspective view thereof; and,

FIG. 10 is a perspective view of the Lavatory basin in a configuration of use.

Any shading and cross-hatching are not features of the design but are utilized to illustrate the surface contours of the lavatory basin design in the drawings. The broken lines show portions of the lavatory basin that form no part of the claimed design.
